REMOTE CONTROL AND INDICATION
SYSTEM

Henry S. Young, Wilkinsburg, Pa., assignor to
The Union Switch & Signal Company, Swiss-
vale, Pa., a corporation of Pennsylvania

Application February 6, 1939, Serial No. 254,847

4 Claims. (Cl. 246—219)

My invention relates to an improved remote control and indication system and particularly to a system for controlling from a remote point a railway track switch and the associated signals, and for providing indications of the condition of the switch and of the signals.

It is an object of my invention to provide an improved system of the type described employing a minimum of line conductors and which is reliable in operation.

A further object of my invention is to provide an improved system which will operate to supply accurate indications of the position of the switch and of the condition of the associated signals, and which, in the event portions of the equipment do not function in the intended manner, will not give any indication whatever of the position of the switch or of the condition of the signals, and, therefore, will not give false indications.

A further object of the invention is to provide an improved remote control and indication system employing a relay energized by current supplied over a control circuit for effecting control of a device, the system incorporating means governed by the device for periodically varying the resistance of the control circuit to thereby produce fluctuations in the value of the current in the control circuit, the system also having means responsive to fluctuations in the value of the current in the control circuit for providing an indication.

Another object of my invention is to provide an improved switch control and indication system.

Other objects of my invention and features of novelty will be apparent from the following description taken in connection with the accompanying drawing.

I shall describe one form of improved control system embodying my invention, and shall then point out the novel features thereof in claims.

In the drawing the single figure is a diagram of a system embodying my invention.

Referring to the drawing, there is shown therein a stretch of railway track A and a branch track B, while a switch W controls movement of trains between the two lines of track. Movement of trains across the switch W from left to right, as viewed in the drawing, is controlled by a signal 1S, while movement of trains from right to left on track A is controlled by a signal AS, and movement of trains from right to left in track B and onto track A is controlled by a signal BS.

The signal 1S has an upper arm 1SA which controls movement of trains from left to right in the track A, while the signal is provided with a lower arm 1SB which controls movement of trains from left to right from track A to track B.

The signals are shown in the drawing as being of the semaphore type, but it should be understood that other types of signals, such as color light or position light signals, may be employed if desired.

The switch W is moved between a normal and a reverse position by suitable power driven switch machine SM which may be either of the electric or of the pneumatic type.

The switch machine SM is controlled by a polarized switch control relay WR, while the switch W has associated therewith a polarized switch repeating relay WPR, a polarized signal control relay HR and a coding relay CT.

A switch control lever SL is provided to control the polarity of the current supplied to the winding of the switch control relay WR and thereby control the switch W, while a signal control lever K is provided to control the polarity of the current supplied to the winding of the signal control relay HR and thereby control the signals associated with the switch W.

The switch control lever SL and the switch indication relay WKR cooperate to control the circuits for energizing the normal switch indication lamp NK and the reverse switch indication lamp RK.

The signal control lever K and the signal indication relay GPR cooperate to control the circuits for energizing the left signal indication lamp LGK and the right signal indication lamp RGK.

The switch control lever SL is movable between a normal and a reverse position and has associated therewith movable contacts 10 and 11. Contact 10 controls the polarity of the current supplied from battery 14 to switch control wires 15 and 16 by means of which current is supplied to the winding of the switch control relay WR.

The control wire 15 is connected to one terminal of the winding of switch control relay WR, while wire 15 has connected in series therewith primary winding 17 of transformer TR1. The control wire 16 serves as a common wire for both the switch and signal control circuits and is connected to one terminal of the winding of the switch control relay WR, and also to one terminal of the winding of the signal control relay HR.

Control wire 16 is constantly connected to the

center terminal C of battery 14, while control wire 15 is connected to contact 10 associated with the switch control lever SL.

When the lever SL is in the normal position 5 as shown, contact 10 engages a stationary contact 18 which is connected by wire 19 to terminal D of battery 14 with the result that current of one relative polarity, which may be considered as normal polarity, is supplied from terminals D and 10 C of the battery 14 to the control wires 15 and 16.

When the switch control lever SL is in the reverse position, contact 10 engages contact 20 which is connected by wire 22 to terminal E 15 of battery 14 so that current of the opposite or reverse relative polarity is supplied from terminals E and C of battery 14 to the control wires 15 and 16.

The switch control relay WR has a neutral contact 25 which when picked up engages a stationary contact 26 which is connected by wire 27 to terminal R of battery 30. Contact 25 is connected by wire 31 to polar contact 32 of relay WR, while contact 32 when in the normal position, as shown, engages a normal polar contact 34 which is connected by wire 35 to the switch machine SM. The switch machine is connected by wire 37 to terminal P of battery 30.

30 When polar contact 32 of relay WR is in the reverse position, it engages reverse polar contact 48 which is connected by wire 41 to the switch machine SM.

The details of the control of the switch machine SM by the relay WR form no part of my invention and any suitable control system for the control of the switch machine may be employed. The control system operates so that when the neutral contact 25 of relay WR is 40 picked up and polar contact 32 is in the normal position, current is supplied to the switch machine SM to cause this machine to move the switch W to the normal position. Similarly, when the neutral contact 25 is picked up and the polar contact 32 is in the reverse position, current is supplied to the switch machine SM to cause the machine to move the switch W to the reverse position.

The circuit of the winding of the relay WR 50 and also of relay HR may be controlled by lock or route relays, not shown, in the manner well known in the art so that the winding of the relay WR can be energized only when it is safe to effect a change in the position of the switch W.

55 The switch W has associated therewith contacts 44 and 45 which are movable in accordance with movement of the switch and which control the supply of current to the winding of the switch repeating relay WPR.

60 When the switch W is in the normal position as shown, contact 44, which is connected by wire 47 to one terminal of the winding of relay WPR, engages contact 48 to which is connected a branch of wire 27 leading from the 65 terminal R of battery 30.

In this position of the switch W contact 45, which is connected by wire 50 to the other terminal of the winding of relay WPR, engages contact 51 to which is connected a branch of wire 37 leading from terminal P of battery 30. Accordingly, in this position of the switch W current of one relative polarity, which may be considered normal polarity, is supplied to the winding of relay WPR.

75 When the switch W is in the reverse position,

contact 45 engages contact 48, while contact 44 engages a contact 52 to which is connected a branch of wire 31.

Accordingly, in the reverse position of the switch W, current of the opposite or reverse 5 relative polarity is supplied to the winding of relay WPR.

The contacts 44 and 45 and the associated stationary contacts are arranged so that the circuit controlled by the contacts 44 and 45 10 is complete only when the switch W is in the normal or the reverse position, and is interrupted when the switch is in transit between these positions.

While the contacts 44 and 45 have been 15 described as being in engagement with the stationary contacts associated therewith when the switch W is in its normal or reverse position, it is contemplated, as is well known in the art, that these contacts may be closed when and 20 only when the switch W is in one or the other of its two positions, and is locked in that position.

The coding relay CT has a winding which is 25 constantly energized from the battery 30, while the relay has a contact 55 which alternately engages a front contact 56 and a back contact 58. The contact 55 may be operated at any suitable frequency, as, for instance, 120 or 180 30 times a minute.

The signal control lever K has a neutral or center position I and is movable therefrom in one direction to a position R in which it conditions the signals associated with the switch W for movement of trains to the right as viewed 35 in the drawing, while the lever K is movable from the center position I in the other direction to a position L in which it conditions the signals associated with the switch W for movement of trains to the left as viewed in the drawing. 40

The lever K has associated therewith contacts 60 and 61 which are movable in accordance with movement of the lever. When the lever K is in the position R, contact 60 engages contact 62 to which is connected a branch of wire 45 19 leading from the terminal D of battery 14, while when the lever K is in the position L, contact 60 engages a contact 64 to which is connected a branch of wire 22 leading from terminal E of battery 14. 50

Contact 60 has connected thereto control wire 65 which has connected in series therewith primary winding 66 of transformer TR2. Control wire 65 is connected to one terminal of the winding of signal control relay HR, the other terminal of which has connected thereto common wire 16 leading from terminal C of battery 14. 55

It will be seen, therefore, that when lever K is in the position R, current of one relative polarity, which may be considered as normal 60 polarity is supplied from terminals D and C of battery 14 to control wires 16 and 65 leading to the winding of signal control relay HR, while when the lever K is in the position L, current of the opposite or reverse relative polarity is supplied from terminals C and E of battery 14 to the control wires 16 and 65. 65

The signal control relay HR and the switch repeating relay WPR cooperate in the manner hereinafter described in detail to control the 70 circuits for the signals associated with the switch W.

The relay HR has a neutral contact 66 to which is connected a branch of wire 27 leading from terminal R of battery 30. Contact 75

66 when picked up engages contact 67 which is connected by wire 68 to polar contact 70 of the relay HR. Contact 70 when in the normal position, as shown, engages polar contact 71 which is connected by wire 72 to contact 74 of switch repeating relay WPR.

75 Relay WPR has a neutral contact 75 which when picked up engages contact 74, while contact 75 is connected by wire 76 to polar contact 78 of the relay. Contact 78 when in the normal position, as shown, engages normal polar contact 80 which is connected by wire 81 to the operating mechanism of the upper signal ISA of signal IS, while this mechanism, as well as the mechanisms of the other signals, has connected thereto a branch of wire 37 leading from terminal P of battery 30.

10 The polar contact 78 of relay WPR when in the reverse position engages reverse polar contact 83 which is connected by wire 84 to the operating mechanism of the lower signal ISB of signal IS.

15 The polar contact 70 of the signal control relay HR, when in the reverse position, engages reverse polar contact 85 which is connected by wire 87 to contact 88 of relay WPR. Relay WPR has a neutral contact 90 which when picked up engages contact 88, while contact 90 is connected by wire 91 to polar contact 93 of the switch 20 repeating relay WPR.

25 Contact 93 of relay WPR when in the normal position, as shown, engages normal polar contact 94 which is connected by wire 95 to the operating mechanism of the signal AS. Contact 93 when in the reverse position engages reverse polar contact 96 which is connected by wire 98 to the operating 30 mechanism of the signal BS.

35 The circuits of the wires 81, 84, 95 and 98 leading to the mechanisms of the signals associated 40 with the switch W may be controlled by route or locking relays in the manner customary and well known in the art or by other means responsive to traffic conditions in the vicinity of the switch W so that the signals can be cleared when and only 45 when it is safe to do so.

40 The transformer TR1 has a secondary winding 100 which is connected through an asymmetric unit or rectifier 101 to the winding of switch indication relay WKR. The relay WKR has a contact 102 which when picked up engages a contact 103 to which is connected a branch of wire 19 leading from the terminal D of battery 14. Contact 102 is connected by wire 104 to lever operated contact 11. When the lever SL is in the normal 45 position N as shown, contact 11 engages contact 105 to which is connected one terminal of normal switch indication lamp NK, the other terminal of which has connected thereto wire 22 leading from terminal E of battery 14. It will be seen, therefore, that when the contact 102 of relay WKR is 50 picked up and the switch control lever SL is in the normal position, the lamp NK is lighted.

55 When the lever SL is in the reverse position R, contact 11 engages contact 107 which is connected 55 to one terminal of the reverse switch indication lamp RK, the other terminal of which is connected to wire 22. It will be seen, therefore, that when the contact 102 of relay WKR is picked up and the lever SL is in the reverse position, the lamp RK is lighted.

60 The transformer TR2 has a secondary winding 110 which is connected through an asymmetric unit or rectifier 111 to the secondary winding of the signal indication relay GPR. The relay GPR 65 has a contact 112 which when picked up engages

a contact 114 to which is connected wire 19 leading from terminal D of battery 14. Contact 112 is connected by wire 115 to contact 61 associated with signal control lever K.

70 When the lever K is in the position R as shown, contact 61 engages contact 117 to which is connected one terminal of right signal indication lamp RGK, the other terminal of which is connected to wire 22. When contact 112 of relay GPR is picked up, therefore, at a time when the lever K is in position R, a circuit is established to illuminate the right signal indication lamp RGK.

75 When the lever K is in the position L, contact 61 engages a contact 118 to which is connected one terminal of the left signal indication lamp LGK, the other terminal of which is connected to wire 22. Accordingly, when contact 112 of relay GPR is picked up and lever K is in position L, a circuit is established to illuminate left signal indication lamp LGK.

80 The windings of the switch control relay WR and of the signal control relay HR are of relatively high resistance, as for example 500 ohms, with the result that relatively little current flows in the control circuits in which these windings are included in series. The continuously operating contact 55 of the coding relay CT operates at times, as explained in detail below, to intermittently shunt the windings of the relays WR and HR, and thus effect an increase in the flow of current in the control circuits for these windings. The resulting pulsations or fluctuations in the value of the current in these circuits causes current to be induced in the secondary windings of the transformers TR1 and TR2 so that current is supplied from these transformer windings to the windings of the indication relays WKR and GPR.

85 The contact 55 of coding relay CT when picked up engages contact 56 which is connected by wire 120 to contact 121 of relay WPR, while relay WPR has a neutral contact 122 which when picked up engages contact 121. Contact 122 is connected by wire 123 to polar contact 124, while polar contact 124 when in the normal position, as shown, engages normal polar contact 126 which is connected by wire 127 to normal polar contact 128 of switch control relay WR.

90 When polar contact 124 is in the reverse position, it engages reverse polar contact 130 which is connected by wire 131 to reverse polar contact 132 of relay WR.

95 The switch control relay WR has a contact 134 which engages the contacts 128 and 132, while contact 134 is connected by wire 135 to contact 136. The switch control relay WR has a neutral contact 138 which when picked up engages contact 136, while contact 138 has a branch of control wire 15 connected thereto.

100 It will be seen, therefore, that when the windings of relays WR and WPR are both energized with current of the same relative polarity so that their polar contacts are in the same relative positions, a circuit is established by the neutral and polar contacts of these relays to connect wire 15 to contact 56 of coding relay CT. When contact 55 of the relay CT is picked up, it establishes connection from contact 56 to wire 16 so that a circuit shunting the winding of switch control relay WR is established between wires 15 and 16.

105 When contact 55 of relay CT is released, it engages contact 58 which is connected by wire 140 to contacts controlled in any suitable manner well known in the art in accordance with the position K.

tion of the signals associated with the switch W. These contacts are controlled in such manner that each contact is open when the signal with which it is associated is displaying the stop indication, while the contact is closed when the associated signal is displaying a proceed indication or when the signal arm or signal mechanism is at any point intermediate the stop and proceed positions.

10 For ease in identification each of the contacts associated with the signals has placed adjacent thereto the reference characters of the signal with which the contact is associated.

The signal ISA has associated therewith a movable contact 142 which engages at times a stationary contact 143 which is connected by wire 144 to normal polar contact 145 of relay HR.

The signal ISB has associated therewith a movable contact 147 which engages at times a stationary contact 146 to which is connected a branch of wire 144.

It will be seen that when either signal ISA or ISB is displaying a proceed indication, connection is established between wire 140 and normal polar contact 145 of relay HR. Similarly, when both signals ISA and ISB are displaying a stop indication, no connection is established from wire 140 to contact 145.

The signal BS has associated therewith a movable contact 148 which engages at times stationary contact 149 which is connected by wire 150 to reverse polar contact 152 of relay HR.

The signal AS has associated therewith movable contact 153 which at times engages contact 155 to which is connected a branch of wire 150.

It will be seen that when either signal AS or BS is displaying the proceed indication, a circuit is established between wire 140 and reverse polar contact 152 of relay HR, while when both of these signals are displaying the stop indication, no connection is established between wire 140 and contact 152.

The signal control relay HR has a polar contact 156 which at times engages the contacts 145 or 152, while contact 156 is connected by wire 157 to contact 158.

The relay HR has also a neutral contact 161 which when picked up engages contact 158, while contact 160 has connected thereto a branch of control wire 65.

It will be seen, therefore, that when the signal control relay HR is energized with current of one or the other relative polarity to condition the signals associated with the switch W to permit movement of trains in one direction or the other across the switch, and when, in addition, one of the signals is displaying the proceed indication, connection is established between control wire 65 and wire 140 leading to contact 58 of coding relay CT.

Accordingly, when contact 55 of relay CT is released and engages contact 58 to thereby establish connection between control wire 16 and wire 140, a circuit shunting the winding of the signal control relay HR is established between the control wires 16 and 65.

The equipment is shown in the drawing in the position which it assumes when the switch control lever SL and the switch W are in their normal positions, and when the signal control lever K is in the position R.

As the switch control lever SL is in the normal position, contact 10 engages contact 18 to which is connected wire 19 leading from terminal D 75 of battery 14 with the result that current of nor-

mal relative polarity is supplied from terminals D and C of battery 14 to the control wires 15 and 16 leading to the winding of the switch control relay WR. Accordingly, the winding of the switch control relay WR is energized with current of normal relative polarity and the neutral contacts 25 and 138 of the relay are picked up, while the polar contacts 32 and 134 are in their normal positions as shown.

As the signal control lever K is in the position R, contact 60 engages contact 62 to which is connected a branch of wire 19 leading from terminal D of battery 14 with the result that current of normal relative polarity is supplied from terminals D and C of battery 14 to the control wires 65 and 16 leading to the winding of the signal control relay HR. Accordingly, the neutral contacts 66 and 160 of signal control relay HR are picked up, while the polar contacts 70 and 156 of this relay are in their normal positions as shown.

At this time as the switch W is in the normal position, current of normal relative polarity is supplied over the circuits controlled by the switch operated contacts 44 and 45 to the winding of the switch repeating relay WPR with the result that the neutral contacts 122, 75 and 90 of this relay are picked up, while the polar contacts 124, 78 and 93 of the relay are in their normal positions as shown.

As the polar contact 134 of switch control relay WR is in the normal position, and as the polar contact 124 of switch repeating relay WPR is also in the normal position, a circuit is established from wire 15 to contact 56 of the coding relay CT. This circuit is traced from wire 15 through neutral contacts 138—136 of relay WR, wire 135, normal polar contacts 134—128 of relay WR, wire 127, normal polar contacts 126—124 of relay WPR, wire 123, neutral contacts 122—121 of relay WPR, wire 120, and contact 56.

When the contact 55 of coding relay CT is picked up, connection is established from wire 16 to contact 56 with the result that a circuit shunting the winding of the relay WR is established. When this circuit is complete, the resistance of the circuit of the control wires 15 and 16 is greatly reduced and there is a corresponding increase in the value of the current flowing in this circuit, and, therefore, in the primary winding 17 of transformer TR1.

On the next operation of the contact 55 of the coding relay CT, it is moved out of engagement with the contact 56, thereby interrupting the circuit shunting the winding of the switch control relay WR. On interruption of this shunt circuit, the winding of the relay WR is again included in series with the circuit of the control wires 15 and 16 with the result that the resistance of this circuit is substantially increased, and there is a corresponding reduction in the value of the current flowing in this circuit, and, therefore, in the primary winding 17 of transformer TR1.

On the next operation of the contact 55 of relay CT it is again moved into engagement with contact 56 to again establish the circuit shunting the winding of relay WR, and there is an increase in the flow of current in the circuit of the control wires 15 and 16, and, therefore, in the primary winding 17 of transformer TR1.

It will be seen that as a result of operation of the contact 55 of coding relay CT, the value of the current flowing in the control wires 15 and 16, and, therefore, in the primary winding 75

17 of transformer TR1, is intermittently varied with the result that current is induced in the transformer secondary winding 100 from which current is supplied through the rectifier 101 to the winding of the switch indication relay WKR.

Accordingly, contact 102 of switch indication relay WKR is picked up, while as the switch control lever SL is in the normal position, contact 11 engages contact 105 so that the circuit of the normal indication lamp NK is complete, and this lamp is illuminated to indicate to the operator that the switch W occupies the normal position.

At this time as the polar contact 78 of switch indication relay WPR is in the normal position and as polar contact 70 of signal control relay HR is also in the normal position, a circuit is established to energize the operating mechanism of signal ISA to cause this signal to display the clear indication.

The circuit for energizing the mechanism of signal ISA is traced from terminal R of battery 30 through wire 27, contacts 66-67 of relay HR, wire 68, normal polar contacts 70-71 of relay HR, wire 72, neutral contacts 74-75 of relay WPR, wire 76, normal polar contacts 78-80 of relay WPR, wire 81 to the mechanism of signal ISA which is connected by wire 31 to terminal P of battery 30.

As the signal ISA is displaying the clear indication, the contact 142 associated with this signal is closed. As the polar contact 156 of relay HR is in the normal position, a circuit is established from control wire 65 to contact 58 of the coding relay CT.

This circuit is traced from control wire 65 through neutral contacts 160-158 of relay HR, wire 157, normal polar contacts 156-145, of relay HR, wire 144, signal controlled contacts 143-142 of signal ISA and wire 140 to contact 58.

On movement of contact 55 of coding relay CT to its released position it engages contact 58 and establishes a circuit between wires 65 and 16 shunting the winding of signal control relay HR.

On movement of contact 55 of coding relay CT into engagement with contact 58 to establish the circuit shunting the winding of signal control relay HR there is a reduction in the resistance of the circuit of the control wires 65 and 16, and a corresponding increase in the flow of current in this circuit, and, therefore, in the primary winding 66 of transformer TR2.

On the next operation of the contact 55 of relay CT it is moved out of engagement with contact 58, thereby interrupting the circuit shunting the winding of signal control relay HR, with the result that the winding of the relay HR is again included in series with the circuit of the control wires 65 and 16. Accordingly, the resistance of this circuit is substantially increased and there is a corresponding reduction in the value of the current flowing in the circuit, and, therefore, in the transformer primary winding 66.

As a result of operation of the contact 55 of relay CT the value of the current flowing in the circuit of which the control wire 65 forms a part is constantly fluctuating with the result that current is induced in the secondary winding 110 of the transformer TR2.

Current, therefore, is supplied from the secondary winding 110 of transformer TR2 through the rectifier 111 to the winding of the signal indication relay GPR. Accordingly, contact 112

of relay GPR is picked up, while as the signal control lever K is in position R at this time, contact 61 establishes a circuit for the right signal indication lamp RGK with the result that this lamp is illuminated to indicate to the operator that the signals associated with the switch W are conditioned for movement of trains to the right.

When the contact 55 of the coding relay CT establishes the circuits shunting the windings 10 of the relays WR and HR, there is a reduction in the degree of energization of these windings. However, the rate of operation of the contact 55 of relay CT is such that the periods during which the windings of the relays WR and HR are shunted are relatively short with the result that the neutral contacts of these relays remain picked up between periods of energization of the relay windings.

Furthermore, when the circuit shunting the winding of either of the relays is established, the relay is rendered slow acting and the relay contacts will not release immediately on a decrease in the degree of energization of the relay winding. This aids in insuring that the relay neutral contacts will remain picked up during the periods in which the circuit shunting the relay winding is established.

With the equipment in the condition shown in the drawing a train traveling from left to right would pass over the switch W and remain on track A. If the operator wishes to cause a train moving from left to right to pass from track A to track B, he may do so by moving the switch control lever SL from the normal position to the reverse position.

On movement of the switch control lever SL from the normal to the reverse position contact 10 is moved out of engagement with contact 18, thereby interrupting the circuit for supplying current of normal relative polarity to the circuit of the control wires 15 and 16, while when the lever SL is in the reverse position, contact 10 engages contact 20 to establish a circuit for supplying current of reverse relative polarity from terminals C and E of the battery 14 to the control wires 15 and 16.

On movement of the lever SL out of the normal position, contact 11 is moved out of engagement with the contact 105 to thereby interrupt the circuit of the lamp NK.

On the supply of current of reverse relative polarity to the circuit of the control wires 15 and 16 the neutral contacts 25 and 138 of relay WR become released and thereafter again pick up, while the polar contacts 32 and 134 are shifted from their normal to their reverse positions.

As a result of release of contact 138 of relay WR and of movement of the polar contact 134 to the reverse position, the previously traced circuit shunting the winding of relay WR is interrupted so that this circuit cannot be established by operation of the contact 55 of the coding relay CT.

Accordingly, the value of the current in the circuit of the control wires 15 and 16 remains constant and no current is induced in the secondary winding 100 of transformer TR1. As a result, the winding of switch indication relay 70 WKR is not energized and contact 102 of the relay is released so that neither switch indication lamp can be illuminated.

As a result of movement of the polar contact 32 of switch control relay WR to the reverse po-

sition, a circuit is established to energize the switch machine SM to cause this machine to move the switch W from the normal to the reverse position.

- 5 On movement of the switch W away from the normal position, the contacts 44 and 45, which are operated in accordance with movement of the switch, are moved out of engagement with the contacts 48 and 51, thereby interrupting the 10 circuit of the winding of the switch repeating relay WPR. When the switch W attains the reverse position, contacts 44 and 45 engage the contacts 52 and 48, respectively, and establish a circuit to supply current of reverse relative polarity to the winding of the switch repeating relay WPR. Accordingly, the neutral contacts 122, 75 and 90 of this relay become picked up, while polar contacts 124, 78 and 93 are shifted to their reverse positions.
- 20 When the polar contact 134 of relay WR and the polar contact 124 of relay WPR are both in their reverse positions, the circuit shunting the winding of switch control relay WR is again established and will be intermittently completed 25 by the coding relay contact 55. Accordingly, there will be fluctuations or pulsations in the value of the current flowing in the circuit of the control wires 15 and 16 with the result that the winding of the switch indication relay WKR will 30 again be energized and the contact 102 will be picked up.

At this time as the switch control lever SL is in the reverse position, contact 11 engages contact 107 so that the circuit of the right switch 35 indication lamp RK is complete and this lamp is illuminated to inform the operator that the switch W is in the reverse position.

On movement of the switch W away from the normal position with resultant interruption of 40 the supply of current to the winding of the switch repeating relay WPR by the contacts 44 and 45, the neutral contact 75 of this relay becomes released, thereby interrupting the circuit for supplying current to the operating mechanism of the signal ISA. Signal ISA, therefore, 45 no longer displays the proceed indication, but instead displays the stop indication. On movement of the signal ISA to the position to display the stop indication the contact 142 associated with the signal is opened, thereby interrupting the previously traced circuit from control wire 65 to contact 58.

Accordingly, contact 55 of the coding relay CT is no longer able to establish the circuit shunting 55 the winding of the signal control relay HR, and accordingly, the current flowing in the circuit of control wires 65 and 16 remains at the same uniform value. As a result, no current is induced in the secondary winding 110 of transformer TR, and the winding of signal indication relay GPR is not energized, while contact 112 is released with the result that the lamp RGK is extinguished.

When the switch W attains the reverse position 65 so that contacts 44 and 45 effect the supply of current of reverse relative polarity to the winding of the switch repeating relay WPR, polar contact 78 of relay WPR is shifted to the reverse position in which it engages contact 83 to thereby establish the circuit for supplying current to the operating mechanism of signal ISA.

This circuit is traced from wire 27 leading from terminal R of battery 30 through contacts 66-67 of signal control relay HR, wire 68, normal polar contacts 70-71 of signal control relay HR,

wire 72, neutral contacts 74-75 of relay WPR, wire 76, reverse polar contacts 78-83 of relay WPR, wire 84, operating mechanism of signal ISA, and wire 31 to terminal P of battery 30.

On energization of the operating mechanism 5 of signal ISA this signal is caused to display the proceed indication, while the contact 147 associated with the signal is closed, thereby reestablishing the circuit from control wire 65 to wire 140 leading to contact 58.

Accordingly, as a result of operation of contact 55 of coding relay CT, the circuit shunting the winding of signal control relay HR is intermittently established, while current is supplied by the transformer TR2 to the winding of signal 15 indication relay GPR, as previously explained. The contact 112, therefore, will be picked up, while as the signal control lever K is still in the position R, its contact 61 engages contact 117 so that the circuit for the lamp RGK is complete, 20 and this lamp is illuminated to indicate to the operator that the signal permitting movement of trains to the right at a time when the switch W is in the reverse position has cleared.

If while the switch W is in the reverse position 25 the operator wishes to return it to the normal position, he may do so by moving the switch control lever SL from the reverse to the normal position. As a result of this movement of the switch control lever SL, contact 10 is moved out 30 of engagement with contact 20, thereby interrupting the supply of current of reverse relative polarity to the control wires 15 and 16, while on movement of the contact 10 into engagement with contact 18 current of normal relative polarity is again supplied to the control wires 15 and 16.

In addition, on this movement of the control 35 lever SL contact 11 is moved out of engagement with contact 107, thus interrupting the circuit 40 for energizing the lamp RK, while the contact 11 is moved into engagement with contact 105 to permit energization of the lamp NK on subsequent picking up of the contact 102 of relay WKR.

On the supply of current of normal relative polarity to the control wires 15 and 16, the neutral contacts of the relay WR become released and thereafter again become picked up, while the polar contacts 32 and 134 are shifted from their 50 reverse to their normal positions.

On movement of contact 134 out of engagement with contact 132 at a time when the switch W is in the reverse position, the circuit for shunting the winding of relay WR is interrupted so that 55 thereafter fluctuations no longer occur in the value of the current flowing in the control wires 15 and 16. Accordingly, no current is supplied by transformer TR1 to the winding of relay WKR and its contact 102 is released.

On movement of contact 32 of relay WR to the normal position a circuit is established to effect operation of the switch machine SM to cause movement of the switch W to the normal position.

On movement of the switch W away from the 65 reverse position the contacts 44 and 45 interrupt the circuit for energizing the winding of relay WPR, and the contact 75 of this relay becomes released to interrupt the circuit for supplying current to the operating mechanism of the signal 70 ISA. Accordingly, the signal ISA no longer displays the proceed indication and is caused to display the stop indication.

When the signal ISA displays the stop indication, the contact 147 is opened, thereby inter- 75

rupting the circuit shunting the winding of relay HR with the result that current of uniform value flows in the circuit of the control wires 65 and 16. Accordingly, signal indication relay GPR is not energized, and its contact 112 is released and interrupts the circuit for energizing the lamp RGK.

When the switch W attains the normal position, current of normal relative polarity is again supplied by contacts 44 and 45 to the winding of switch repeating relay WPR and the polar contacts of this relay are shifted to their normal positions while the neutral contacts of the relay become picked up. On movement of polar contact 78 to the normal position and on picking up of neutral contact 75, the previously traced circuit for supplying energy to the operating mechanism of signal ISA is established with the result that this signal again displays the proceed indication.

20 In similar manner, when polar contact 124 of relay WPR is in the normal position and neutral contact 122 is picked up, the previously traced circuit for establishing connection between control wire 15 and contact 56 of coding relay CT 25 is again complete, and contact 55 of the coding relay will intermittently establish the circuit shunting the winding of relay WR. Accordingly, current will be supplied by the secondary winding 100 of transformer TR1 to the switch indication 30 relay WKR, and contact 102 will become picked up to establish the circuit to illuminate the normal indication lamp NK.

In addition, on operation of signal ISA to display the proceed indication contact 142 is closed 35 to again establish the circuit from control wire 65 to wire 140 leading to contact 58 of coding relay CT so that the contact 55 intermittently establishes the circuit shunting the winding of signal control relay HR. As a result, current will 40 be supplied by the transformer TR2 to the winding of signal indication relay GPR, and the contact 112 of this relay will be picked up to establish the circuit to illuminate lamp RGK.

If the operator wishes to condition the signals 45 associated with the switch W for movement of trains from right to left, he may do so by moving the signal control lever K from the position R to the position L.

For purposes of illustration, it will be assumed 50 that this movement of the lever K takes place at a time when the switch W is in the normal position.

On movement of the signal control lever K from the position R to the position L contact 60 is 55 moved out of engagement with contact 62, thereby interrupting the supply of current of normal relative polarity to the circuit of the control wires 65 and 16, while when contact 60 is moved into engagement with contact 64 it effects the supply 60 of current of reverse relative polarity from terminals C and E of battery 14 to the control wires 65 and 16.

In addition, on this movement of the signal control lever K, contact 61 is moved out of engagement with contact 117 to thereby interrupt the circuit of lamp RGK, while when lever K is in position L, contact 61 engages contact 118 so that lamp LGK will be lighted on picking up of contact 112 of relay GPR.

70 On the supply of current of reverse relative polarity to the control wires 65 and 16 the neutral contacts 68 and 160 of signal control relay HR become picked up, while the polar contacts 70 and 156 of the relay are shifted from their normal 75 to their reverse positions.

On movement of polar contact 70 of signal control relay HR from its normal to its reverse position it interrupts the circuit from wire 27 to wire 72, and thereby prevents the supply of current to the mechanism of either of the signals at signal 5 ISA.

On movement of the contact 70 of relay HR to the reverse position it engages contact 85 and establishes a circuit to permit current to be supplied to the mechanism of the signal AS or signal 10 BS as determined by polar contact 93 of switch repeating relay WPR.

On movement of polar contact 156 of relay HR to the reverse position it engages contact 152 to thereby permit a circuit to be established between 15 control wire 65 and wire 140 on closing of the contact 143 associated with signal BS or contact 153 associated with signal AS.

On initial movement of contact 156 of the signal control relay HR to the reverse position 20 neither of the contacts 148 or 153 is closed, and hence no circuit is established by contact 55 of coding relay CT to shunt the winding of relay HR. Accordingly, current of the same uniform value is present in the circuit of the control wires 25 65 and 16. At this time, therefore, no current is supplied by the transformer TR2 to the winding of the signal indication relay GPR, and the contact 112 of this relay is released with the result that both of the signal indication lamps RGK and 30 LGK are dark.

As the switch W is assumed to be in the normal position at the time the signal control lever K is moved from position R to position L, the winding of the switch repeating relay WPR will 35 be supplied by contacts 44 and 45 with current of normal relative polarity, and the polar contact 93 of this relay will be in the normal position as shown. Accordingly, on movement of contact 70 of relay HR to the reverse position, in 40 which it engages contact 85, a circuit is established to effect the supply of current to the mechanism of signal AS. This circuit is traced from wire 27 leading from terminal R of battery 30 through neutral contacts 66-67 of relay 45 HR, wire 68, reverse polar contacts 70-85 of relay HR, wire 87, contacts 88-90 of relay WPR, wire 91, normal polar contacts 93-94 of relay WPR, wire 95, mechanism of signal AS, and wire 37 to terminal P of battery 30.

As a result of the supply of current to the operating mechanism of signal AS, this signal is caused to display the proceed indication, while contact 153 associated with the signal becomes closed and engages contact 155, thereby 55 completing the circuit from wire 65 to wire 140. This circuit is traced from wire 65 through neutral contacts 160-158 of relay HR, wire 157, reverse polar contacts 156-152 of relay HR, wire 150, signal controlled contacts 155-153, and 60 wire 140 to contact 58 of coding relay CT.

At this time, as a result of operation of the contact 55 of coding relay CT, the circuit shunting the winding of signal control relay HR is 65 intermittently completed with the result that there are fluctuations in the value of the current flowing in the circuit of the control wires 65 and 16.

At this time, therefore, current will be supplied to transformer TR2 to the winding of signal indication relay GPR and the contact 112 of this relay will be picked up. At this time as signal control lever K is in position L, contact 61 engages contact 118 so that a circuit is estab- 70 75

lished to energize the lamp LGK which is thereupon lighted.

It should be observed that during the movement of the signal control lever K from position R to position L, the switch control lever SL and the switch W remained in the normal position. Accordingly, the circuit for shunting the winding of relay WR was maintained and the relay WKR continued to be energized and the 10 normal switch indication lamp NK was maintained energized.

If at this time, that is, while lever K is in position L, the operator wishes to condition the switch W and the associated signals for movement of a train from right to left from track B onto track A, he may do so by effecting movement of the switch W from the normal to the reverse position.

In order to effect this movement of the switch 20 W the switch control lever SL is moved from the normal position to the reverse position, thereby effecting the supply of current of reverse relative polarity to the control wires 15 and 16.

On the supply of current of this relative polarity 25 to the winding of relay WR polar contact 32 of relay WR is shifted to the reverse position and effects the supply of current to the switch machine SM to cause the machine to move the switch W from the normal to the reverse position. In addition, contact 134 of relay WR is shifted to the reverse position, thereby interrupting the circuit for shunting the winding of relay WR.

As long as the circuit for shunting the winding 35 of relay WR is interrupted, current of the same uniform value is present in the circuit of the control wires 15 and 16 and no current is supplied by transformer TR1 to the winding of relay WKR with the result that the contact 102 of 40 this relay is released and both of the switch indication lamps NK and PK are dark.

On movement of the switch W away from the normal position the contacts 44 and 45 interrupt the circuit of the winding of the switch 45 repeating relay WPR, and the neutral contacts of this relay become released with the result that contact 90 interrupts the circuit for supplying current to the mechanism of signal AS and this signal is thereupon caused to display a stop indication.

When signal AS displays a stop indication, contact 153 associated with the signal is open and interrupts the circuit for shunting the winding of signal control relay HR with the result 55 that current of the same uniform value is present in the circuit of the control wires 65 and 16, and no current is supplied by transformer TR2 to signal indication relay GPR. Accordingly, contact 112 of relay GPR is released and the signal indication lamps RGK and LGK are both dark.

When the switch W completes its movement to the reverse position, contacts 44 and 45 effect the supply of current of reverse relative polarity 65 to the winding of relay WPR and the neutral contacts of this relay thereupon become picked up, while the polar contacts of the relay are shifted to their reverse positions.

On picking up of neutral contact 90 and shifting of polar contact 93 to the reverse position in which it engages contact 96, a circuit is established to supply current to the mechanism of signal BS.

75 This circuit is traced from wire 27 leading

from terminal R of battery 30 through neutral contacts 66-67 of relay HR, wire 68, reverse polar contacts 70-85 of relay HR, wire 87, neutral contacts 88-90 of relay WPR, wire 91, reverse polar contacts 93-96 of relay WPR, and 5 wire 98 to one terminal of the mechanism of signal BS, the other terminal of which is connected by wire 37 to terminal P of battery 30.

As the mechanism of signal BS is energized, this signal is conditioned to display the proceed 10 indication and when the signal is displaying the proceed indication, contact 148 associated with the signal is closed and engages contact 149 to establish connection between control wire 65 and wire 140 leading to contact 58 of coding relay 15 CT. Accordingly, the circuit shunting the winding of relay HR is intermittently completed by contact 55 of coding relay CT, and current is supplied by transformer TR2 to the winding of relay GPR. As lever K is in position L, contact 20 61 engages contact 118 so that on picking up of contact 112 of relay GPR, lamp LGK is illuminated.

Similarly, on picking up of neutral contact 122 25 of relay WPR, and on movement of polar contact 124 to the reverse position at a time when contact 134 of relay WR is also in the reverse position, the circuit for shunting the winding of the switch control relay WR is established and will be intermittently completed by the contact 30 55 of coding relay CT. As a result, current will be supplied by transformer TR1 to switch indication relay WKR and contact 102 will be picked up. At this time contact 11 associated with the switch control lever SL engages contact 107 so 35 that the reverse indication lamp RK is illuminated.

The system operates in substantially the same manner if while the signal control lever K is in position L it is desired to effect movement of the 40 switch W from the reverse to the normal position. On this movement of the switch W and resultant change in the position of the contacts of switch repeating relay WPR, signal BS will be caused to display a stop indication, while when 45 the switch W completes its movement, signal AS will again be conditioned to display the proceed indication as previously described.

In similar manner, if while the signal control lever K is in the position L, in which it conditions the signals for movement of trains from right to left, the operator desires to condition the signals for movement of trains from left to right, he may do so by returning the signal control lever K to the position R.

On this movement of the signal control lever K the polar contact 79 of the signal control relay HR is conditioned to interrupt the circuits for supplying energy to both the signals AS and BS, and to establish a circuit for supplying energy 60 to the operating mechanism of one of the signals ISA or ISB, the particular one depending upon the position occupied by the polar contacts of the switch repeating relay WPR.

It will be seen that the circuit shunting the 65 winding of the switch control relay WR is controlled jointly by the contacts of the relay WR and of the switch repeating relay WPR. It will be seen also that this circuit can be completed by the contact of the coding relay CT when 70 and only when the neutral contacts of relays WR and WRP are picked up, and the polar contacts of these relays are in the same relative positions. This insures that an indication of the position occupied by the switch W will be provided only 75

when both relays WR and WRP are energized and the positions of the switch W and the polar contacts of the switch control relay WR are in agreement.

- 5 Similarly, the circuit shunting the winding of signal control relay HR is controlled by contacts of the switch repeating relay WRP, by contacts of the signal control relay HR and also by contacts associated with the signals. It will be seen 55
 10 also that the circuit shunting the winding of the relay HR can be established by the contact 10 of the coding relay CT when and only when the relays WPR and HR are both energized and the polar contacts of these relays are in the same 15 relative positions, and when, in addition, the contact associated with an appropriate one of the signals is closed.

In addition, it will be seen that in the system shown in this application the control wire 16 is 20 common to the control circuits for both the switch control relay WR and for the signal control relay HR.

It will be seen also that when the contact 55 of coding relay CT is effective to establish the 25 circuits shunting the windings of the relays WR and HR, at which time current of unusually high value is present in the control circuits for these 30 relays, the circuits shunting the relay windings are alternately established, while both shunt circuits are not complete at the same time.

This arrangement prevents the current of high 35 value in the switch control relay control circuit and in the signal control relay control circuit being present simultaneously in the common wire 16, which would be the case if the circuits shunting the windings of the relays WR and HR were 40 established at the same time. Accordingly, the load placed on the wire 16 is held at the minimum value.

40 In the system provided by this invention, in order for an indication to be given of the position of the switch W or of the condition of the signals associated with the switch, fluctuations or pulsations must occur in the current in the control circuit of the switch control relay or of the signal control relay. If for any reason, such as failure of the apparatus to function in the intended manner, these fluctuations or pulsations fail to occur, when they should, no indication will be given, 45 and hence, the system will not operate at such times to give a false indication.

While the system provided by this invention has been illustrated and described in connection with remote control of a railway track switch 55 and the associated signals, it should be understood that the invention is not limited to use in this manner, and that it may be employed wherever similar operating conditions are encountered.

Although I have herein shown and described 60 only one form of remote control and indication system embodying my invention, it is understood that various changes and modifications may be made therein within the scope of the appended claims without departing from the spirit and 65 scope of my invention.

Having thus described my invention, what I claim is:

1. In combination, a first control device having a winding, a second control device having a winding, a first control circuit including a first wire and a common wire for supplying current to the winding of the first control device, a second control circuit including the common wire and a second control wire for supplying current to the 70 winding of the second control device, means for 75 supplying current to the first control circuit, means for supplying current to the second control circuit, means controlled by the first control device, means controlled by the second control device, each of said control devices being operative when energized to effect a predetermined condition of the means controlled thereby, the means controlled by each control device controlling a circuit for shunting the winding of the said control device, and means for alternately completing said shunt circuits to thereby produce fluctuations in the value of the current in said control circuits, each of said control circuits having associated therewith indication means responsive to fluctuations in the value of the current 10 in such circuit. 15

2. In combination, a first control device having a winding, a second control device having a winding, a first control circuit including a first wire and a common wire for supplying current to the winding of the first control device, a second control circuit including the common wire and a second control wire for supplying current to the winding of the second control device, means for supplying current to the first control circuit, means for supplying current to the second control circuit, means controlled by the first control device, means controlled by the second control device, each of said control devices being operative when energized to effect a predetermined condition of the means controlled thereby, the means controlled by each control device controlling a circuit effective when established to produce an increase in the value of the current in the control circuit for such control device, means for alternately establishing said circuits to thereby produce fluctuations in the value of the current in said control circuits, each of said control circuits having associated therewith means responsive to fluctuations in the value of the current 20 in such circuit. 25

3. In combination, a first control device having a winding, a second control device having a winding, a first control circuit including a first wire and a common wire for supplying current to the winding of the first control device, a second control circuit including the common wire and a second wire for supplying current to the winding of the second control device, means for supplying current to the first control circuit, means for 30 supplying current to the second control circuit, means controlled by the first control device, means controlled by the second control device, each of said control devices being operative when energized to effect a predetermined condition of the means controlled thereby, the means controlled by each control device controlling a circuit effective when established to produce an increase in the value of the current in the control circuit for such control device, means for alternately establishing said circuits to thereby produce fluctuations in the value of the current in said control circuits, each of said control circuits having associated therewith means responsive to fluctuations in the value of the current 35 in such circuit. 40

3. In combination, a first control device having a winding, a second control device having a winding, a first control circuit including a first wire and a common wire for supplying current to the winding of the first control device, a second control circuit including the common wire and a second wire for supplying current to the winding of the second control device, means for supplying current to the first control circuit, means for 45 supplying current to the second control circuit, means controlled by the first control device, means controlled by the second control device, each of said control devices being operative when energized to effect a predetermined condition 50 of the means controlled thereby, the means controlled by each control device controlling a circuit effective when established to produce an increase in the value of the current in the control circuit for such control device, means for alternately establishing said circuits to thereby produce fluctuations in the value of the current in said control circuits, a first transformer having a primary winding connected in series with the first control wire, indication means controlled by current supplied by the secondary winding of said transformer, a second transformer having a primary winding connected in series with the second control wire, and indication 55 means controlled by current supplied by the secondary winding of said second transformer. 60

4. In combination, a railway track switch movable between a normal and a reverse position, a plurality of signals governing movement of trains across said switch, a first control device 65

70

75

having a winding, said device being operative when its winding is energized with current of one relative polarity to effect movement of the switch to one position and being operative when 5 its winding is energized with current of the other relative polarity to effect movement of the switch to the other position, a second control device having a winding, said second control device being operative when its winding is energized with 10 current of one relative polarity to permit clearing of one of said signals and being operative when its winding is energized with current of the other relative polarity to permit clearing of a different one of said signals, a first control 15 circuit including a first wire and a common wire for energizing the winding of the first control device, a second control circuit including the common wire and a second wire for energizing

the winding of the second control device, means for selectively supplying current of one or the other relative polarity to the first control circuit, means for selectively supplying current of one or the other relative polarity to the second control 5 circuit, means governed by the position of the switch for establishing a circuit shunting the winding of the first control device, means governed in accordance with the condition of said signals for establishing a circuit shunting the 10 winding of the second control device, and means for alternately completing said shunt circuits to thereby produce fluctuations in the value of the current in said control circuits, each of said control circuits having associated therewith indication means responsive to fluctuations in the 15 value of the current in such circuit.

HENRY S. YOUNG.
